UNITED STATES PATENT OFFICE.

ARTHUR O. BAYER, OF PHILADELPHIA, PENNSYLVANIA.

DESIGN FOR A TEXTILE FABRIC.

Application filed February 5, 1923. Serial No. 5,086. Term of patent 7 years.

To all whom it may concern:

Be it known that I, ARTHUR O. BAYER, a citizen of Germany, residing in Philadelphia, in the county of Philadelphia and State of Pennsylvania, United States of America, have invented a new, original, and ornamental Design for Textile Fabric, of which the following is a specification, reference being had to the accompanying drawing, forming part thereof.

The drawing shows a plan view of a piece of textile fabric showing my design.

I claim:

The ornamental design for textile fabric, as shown.

ARTHUR O. BAYER.
